ABSTRACT

A holder for a rotary brush assembly formed by two strip-like members which are secured together along their lengths to form a center shaft opening and diametrically opposed circumferential channels extending from one end of the holder to the other.

ROTARY BRUSH ASSEMBLY

BACKGROUND OF THE INVENTION

This invention relates generally to rotary brush assemblies of the type used in cleaning apparatus such as vacuum or suction cleaners, and more specifically to a new and improved brush holder for such assemblies.

Brush assemblies of the type described are typically comprised of a cylindrical roll body which carries a helical brush strip and a beater bar insert. A conventional practice is to make the rolls from wooden dowels which are provided at their ends with bearing inserts and metal caps. This conventional practice has a number of disadvantages which to a large extent are due to the effects of humidity on the wood. In general, changes in humidity can cause wooden dowels to crack, split and/or warp and can cause difficult production problems. For example, if the dowels expand or go out of round because of humidity changes, it may be impossible to assemble the metal end caps. Conversely, if the wood shrinks, the end caps may fall off and/or the dowels may be split by the bearing inserts. Shrinkage and expansion of the wood can also make it difficult to securely attach the brush bristles and beater bars to the dowels.

Additional disadvantages of brush assemblies made with wooden dowels include the necessity of weighting the beater bar inserts which are normally lighter than the brush strips in order to achieve dynamic balance, and the fact that such assemblies are not suitable for wet applications because of the danger or warpage.

Attempts have been made to avoid the foregoing problems by using brush rolls or holders made of plastic or metal. Many of these prior art metal and plastic designs do not have the strength and rigidity to resist twisting and/or deflection during rotation. Another disadvantage of many of the prior art designs is that the rolls or holders are made in several sections which must be accurately aligned and secured together during assembly. Such assembly operations are often complicated and expensive.

SUMMARY OF THE INVENTION

An object of the present invention is to provide a new and improved brush holder which is of an economical and efficient construction.

Another object of the present invention is to provide a new and improved brush holder which has the strength and rigidity necessary to resist twisting and/or deflection during rotation and which is capable of being economically manufactured.

A more specific object of the present invention is to provide a new and improved brush holder characterized by a pair of symmetrical members which can be economically made in straight sections, as by stamping, rolling or extrusion, and then connected together to provide channels for mounting a brush strip and beater bar element.

A further object of the present invention is to provide a new and improved brush holder comprising a pair of symmetrical strip-like members each having a semi-cylindrical central portion, radially extending webs along the edges of the central portion, and outer channel-defining portions integral with the webs, the members being stamped, rolled or extruded in straight sections which are connected together along their lengths and, if desired, twisted 180° about their longitudinal

axis, so that the channel-defining portions form diametrically opposed channels extending from one end of the holder to the other.

Further objects, advantages and a fuller understanding of the invention will be had from the following detailed description and the accompanying drawing.

BRIEF DESCRIPTION OF THE DRAWING

FIG. 1 is an elevational view of a rotary brush assembly constructed in accordance with the present invention; and

FIG. 2 is an end elevational view of the assembly shown in FIG. 1.

DESCRIPTION OF THE PREFERRED EMBODIMENTS

Referring to the drawing, there is shown a brush assembly 10 which is comprised of a holder 11, a brush strip 12 and a beater bar element 13. The assembly 10 is adapted to be mounted for rotation by a power driven shaft (not shown) extending axially through the holder 11.

As shown in the drawing, the holder 11 consists of two symmetrical members, each including as an integral structure a semi-cylindrical central portion 18, radially extending webs 19 along the edges of the central portion 18, and outer channel-defining portions 20. The holder sections may be stamped, rolled or extruded from metal in longitudinally straight sections 30 which are then suitably connected together, as by spot welding the webs 19, so that the central portions 18 define a cylindrical shaft opening 21 and the outer portions 20 cooperate to form diametrically opposed channels 22, 23.

The channels 22, 23 define seats for the brush strip 12 and the beater element 13, respectively. According to one preferred method of manufacture, the connected holder members are twisted 180° about their longitudinal axis, whereby each channel 22, 23 extends helically from one end of the holder 11 to the other. Alternatively, the holder 11 may be left straight so that the channels 22, 23 extend parallel to the longitudinal axis of the holder.

The illustrated brush strip 12 is a conventional structure comprised of a backing member 28 made of a deformable, resilient material such as plastic and bristle tufts 29 which are suitably secured to the backing member 28 along its length. The beater element 13 is made of a material similar to that of the member 28. Both elements 12, 13 are formed as straight strips having grooves along their sides, and are assembled by being flexed and wedged into the channels 22, 23 with the edges of the channels engaged in the grooves.

It will thus be apparent that the invention achieves the objective of providing a brush holder construction which can be efficiently and economically manufactured and, at the same time, has the strength and rigidity to resist twisting and/or flexing during rotation.

Many other variations and modifications of the invention will be apparent to those skilled in the art in view of the foregoing detailed disclosure. Therefore, it is to be understood that, within the scope of the appended claims, the invention can be practiced otherwise than is specifically shown and described.

What is claimed is:

1. A rotary brush assembly comprising a pair of elongated, symmetrical metal members, each of said mem-

including as an integral structure a center portion, ally extending webs along both longitudinal edges aid center portion and a channel-defining portion at the outer edge of each web, said webs of both members being secured together in face-to-face contact with said center portions being spaced apart to define a shaft opening extending the length of said assembly and with said channel-defining portions cooperating to form diametrically opposed channels, each of channels having a closed bottom at the outer edge

10

of the connecting web, spaced side-walls extending radially outwardly from said bottom and a mouth which is open along the length of said assembly, and a flexible strip means seated in each channel and engaged between the sidewalls thereof.

2. A brush assembly as claimed in claim 1 wherein said members are twisted about the longitudinal axis of said assembly so that said channels extend helically.
